UNITED STATES PATENT OFFICE.

ELMER E. SAMPSON, OF LONDON MILLS, ILLINOIS.

RAILWAY-GATE.

No. 900,125.

Specification of Letters Patent.

Patented Oct. 6, 1908.

Application filed April 24, 1907. Serial No. 369,953.

To all whom it may concern:

Be it known that I, ELMER E. SAMPSON, a citizen of the United States, residing at London Mills, in the county of Fulton, State of Illinois, have invented certain new and useful Improvements in Railway-Gates; and I do hereby declare the following to be a full, clear, and exact description of the invention, such as will enable others skilled in the art to 10 which it appertains to make and use the same.

This invention relates to new and useful improvements in railway gates, and it has particular reference to railway gates of that 15 type which are automatically operated by the approach of a train from either direction, means being included for restoring the gates and the parts associated therewith to initial or normal position after each actuation 20 thereof, as the train moves away from the crossing or other place where the gates are placed.

More particularly the invention comprises gates which bridge the track rails and gates 25 which bridge the crossing. The track rail gates serve in their normal position as cattle guards and as a means for preventing persons from carelessly walking between the rails upon which a train is moving. Aside 30 from this function they are employed conjunctively with the crossing gates, and during the passage of a train over the crossing serve, with the crossing gates to close said crossing. These track rail gates are also operable in the event of the crossing gates 35 becoming out of order or inoperative from any cause.

In connection with the crossing gates and the track rail gates the invention resides in 40 the provision of novel actuating means comprising members which are supported, preferably from the inner sides of the track rails, and elements connecting said members with the operating mechanisms of the track rail 45 and crossing gates. Such elements are of novel construction and arrangement and their action upon the gate operating mechanisms is gradual or step by step, whereby sudden shocks or vibrations of the gate and their 50 associated connections in operation, will be eliminated, or reduced to a minimum.

The invention aims as a further object to provide track rail gates of novel construction and which are capable of yielding or rocking 55 horizontally so as to pass snow, dirt, or other

obstructions, which may accumulate upon the tracks.

Inter alia the invention aims to provide a novel construction, combination and arrangement of parts, the details of which will appear in the course of the following description, in which reference is had to the accompanying drawings forming a part of this specification, like characters of reference designating similar parts throughout the several views, wherein:

Figure 1 is a plan view of the gates and the gate operating mechanisms together with the tracks at the crossing, which as shown, is of the street grade type. Fig. 2 is a plan view 70 showing the tracks together with the operating elements at a distance from the crossing, the arrangement being duplicated at each side thereof. Fig. 3 is a side elevation of one of the crossing gates of which four are preferably employed and are arranged in coöperating pairs which bridge the tracks at each side of the crossing. Fig. 4 is a top plan view of such gate. Fig. 5 is an enlarged detailed side elevation looking at the inner side 80 of one of the crossing gates showing the connections for operating the same and the mechanical connections for sounding an alarm. Fig. 6 is an end elevation of such gate. Fig. 7 is a detailed perspective view showing the 85 members or elements of the connections between the track members and the gate operating mechanism, in their detached relation. Fig. 8 is an enlarged plan view of the operative connections between the track members 90 and the connecting elements. Fig. 9 is an enlarged plan view of connections mounted adjacent the crossing gates and on the inner sides thereof for sustaining the latter in position to clear the track during the passage 95 of a train over the crossing and while the other elements of the gate controlling mechanism are "dead" in so far as their operative influence is concerned. Fig. 10 is a vertical section on the line 10—10 of Fig. 3 looking 100 in the direction of the arrow and showing the mount for the track rail gate, whereby the latter may swing to either side in clearing obstructions as indicated by the dotted lines. Figs. 11 and 12 are fragmentary top plan and 105 transverse sectional views of a modified embodiment of the invention, residing more particularly in a disengageable cushioning connection between the elements which operate the crossing gates. Fig. 13 is a fragmen- 110

tary detail view of the yoke of the cushioning connection.

Referring specifically to the accompanying drawings, the numeral 1 designates the track rails and the numeral 2 designates generally the crossing. The rails 1 are connected by the usual cross ties 3 which may be of wood or other suitable construction ordinarily employed in railroad engineering. Supplemental ties 4 are provided at the crossing 2, which project considerably on either side of the rails. At the ends of the ties 4 are vertical posts 5 upon which are pivoted the crossing gates 6, the latter having vertical swinging movement and carrying below their pivots the usual counterbalance weights 7. Between the respective rails 1 and the posts 5, vertical posts 8 are mounted, the latter carrying upper and lower inwardly projecting brackets 9, which serve as bearings for vertical rock shafts 10 carrying at their upper ends visual signals 11, of usual construction.

The track rail gates are designated generally by the numeral 12, and are counterparts in construction. Each of said gates comprises a rectangular frame 13, preferably constructed of angle iron for the purposes of strength and inexpensiveness and including a centrally located vertical reinforcing bar 14, which extends in parallelism to the side bars 15 of said frame. The frame 13 is formed to support a wire filling 16 of conventional type which is strong enough to serve as a cattle guard, three strand wire being preferably employed. Each shaft 10 is formed adjacent its lower end with a collar 17 upon which is supported an auxiliary frame 18, the latter being of nearly triangular shape and including a horizontal top bar 19 which extends on each side of said frame and has its front portion shaped to afford a pintle 20. The pintle 20 is projected loosely through the adjacent end bar 15 and through the reinforcing bar 14 and in such disposition affords a horizontal pivot for the gate 12, whereby the latter may swing in either direction to clear obstructions as previously intimated and as shown more particularly by the dotted lines of Fig. 10, such swinging movement being effected by the pressure of the obstruction upon the gate, the latter returning to normal position in a vertical plane by gravity after it has cleared the obstruction. Positive means are also provided for accomplishing this last named action, and incidentally for cushioning the swinging movement of the gate, such means specifically comprising a retractile coil spring 21 having its upper end engaged with a pin 22 carried by the adjacent bar 15 and having its lower end engaged with a pin 23 carried by the base of the frame 18. The shaft 10 is projected loosely through the upper and lower bars of said frame 18 and operates the gate in its movement to close the

crossing and clear the track by virtue of resilient cushioning connections. With this object in view the shaft 10 carries adjacent its upper end a fast two armed lever 24. The bar 19 above referred to carries at its rear end an upwardly extending headed pin 25 and two retractile coil springs 26 have their rear ends engaged with the pin 25 and their front ends engaged with the respective arms of the lever 24. In like manner the pintle 20 is formed adjacent its front end with a headed pin 27, with which are engaged the front ends of respective retractile coil springs 28, the latter having their rear ends engaged with respective links 29, which are in turn pivotally connected to the respective arms of the lever 24. The shaft 10 is formed at its lower end with a fast laterally projecting lever 30 which has connection with the gate operating mechanism to be more fully described hereinafter.

As previously noted, sudden shocks and vibrations are eliminated during the action of the gate by reason of the provision of the step by step operating mechanism. This result is promoted by the provision of the springs 26 and 28, which serve as resilient connections between the shafts 10 and the respective gates 12 whereby the latter are swung in the performance of their functions upon rocking movement of the former. It is also to be noted that with the gates 12 in either of their extreme positions, the operating mechanism will not become deranged should a vehicle or other object strike said gates with force, this advantage being obtained by virtue of the yielding nature of the connecting elements 26 and 28.

As noted in the introduction, the invention aside from the novel construction of track gates above described, resides in the novel construction, combination and arrangement of correlated parts constituting the gate operating mechanism. Such mechanism comprises essentially members 31 arranged in parallelism to the respective rails 1 and constructed of sections 31', rigidly connected as a series by bolts or other approved fastening means 32. The members 31 are likewise connected to brackets 33, carried at relatively opposite sides upon respective cross links 34, the latter being arranged on each side of the several ties 3, and at their ends having pivotal connection with the aligned arms of T levers, the latter being pivoted at the junction of their arms as at 35 to the ends of the respective ties. Any number of such levers may be employed along one side of the track and inasmuch as some of them differ in function as a series from the others as a series, different numerals will be employed to distinguish the different series. Accordingly the three T levers at the end of the entire series as shown in Fig. 2 are designated by the numeral 36, their aligned arms by the nu-

meral 36' and their angular arms by the numeral 36''. In like manner the fourth **T** lever is designated by the numeral 37, its alined arms by the numeral 37', and its angular arm by the numeral 37''. The remaining **T** levers of the series are correspondingly designated by the numerals 38 and their respective arms 38' and 38''. On the opposite side of the track ordinary two armed levers 10 are employed which are pivoted centrally thereof, as at 39, and which are designated by the numerals 40, 41 and 42 in accordance as they correspond with the respective levers 36, 37 and 38.

15 At this point it is thought best to describe the gate operating mechanism and later on to describe the connections between the levers above noted and such mechanism. The gate operating mechanism is duplicated at 20 each side of the crossing and comprises essentially a prime lever 43 which is pivoted at 44 centrally or, to be more exact, between the ends of a strap 45, the latter having one end fixed as at 46 to the adjacent member 31 25 at one side thereof and at its other end being formed with a slot 47 through which is engaged a pin 48 carried upon the adjacent tie 3. The pin 48 serves to center and guide the strap 45 when the latter is moved with the 30 member 31 to which it is connected. The lever 43 forms a common element of two mechanisms, the one being employed to operate the track gates and to complete the operation of the crossing gates when the 35 train first enters the block defined by the gate operating mechanism, and the other being employed to sustain the several gates in the positions to which they have been previously moved as the train approaches, such 40 last named mechanism including elements coöperating with the lever 43 and to be hereinafter described. The connections for operating the lever 43 from the extreme ends of the block are constituted of a **T** lever 49 pivoted to a tie 3 at one side of the crossing 2 and comprising alined arms 49' and an angular arm 49''. The angular arm 49'' has pivotal connection with a link 50 which is likewise pivoted at 51 to the lever 43 adjacent the inner end thereof, the pivot 51 also serving as a pivotal connection for a link 52 similar to the link 50 and having its end pivotally engaged with a bell crank lever 53 pivotally mounted as at 54 upon the same tie 3 which carries the 55 lever 49.

Means for operating the lever 43 consists of a link 55, which is pivoted as at 56, to a bracket 57 carried by the member 31 opposite the member to which the strap 45 is secured 60 said bracket 57 being formed at its inner end with a slot 58 through which is engaged a pin 59 carried by the lever 43. Said lever 43 at its extreme inner end has pivotal connection with a link 60 which is in turn pivoted to 65 the lever 30 carried upon the lower end of

the shaft 10. The levers 53 are on opposite sides of the crossing as well as of the track and each is connected to its respective lever 49 by a link 61. By virtue of this arrangement operation of either of the levers 49 will 70 operate the other lever 49, and the levers 53 together with the parts associated therewith. The links 60 connect each respective lever 43 with a gate 12 at the adjacent side of the crossing. For the purpose of connecting 75 each lever 43 with the gate 12 at the other side of the track, a two armed lever 62 is provided which is pivoted as at 63 to a strap 64 mounted transversely between each respective pair of ties 4 and adjacent ties 3. The 80 lever 62 has one end thereof, operatively engaged with the lever 43 by means of a connecting link 65 and its other end operatively engaged with the arm 30 of the other gate 12 by a connecting link 66. The gates 6 are 85 operated in corresponding pairs at each side of the track by virtue of connections with prime levers 67 and 68, the lever 67 being of the bell crank type and pivoted as at 69 upon the tie 4 and the lever 68 being a **T** 90 lever and pivoted as at 70 upon a bracket 71 projecting from the other tie 4.

The lever 67 operates the gates 6 on each side thereof, and accordingly has connection by means of links 72 and 73, with oppositely 95 arranged bell crank levers 74 and 75, pivoted upon the posts 5 and having their projecting angular ends connected by links 76 with the gates 6 above the pivots thereof. The link 72 acts upon the lever 74 to lower the gates 100 6 connected therewith by a pulling action, and the link 73 operates the lever 75 to lower the gates 6 connected therewith by a pushing action. The link 72 is designed to operate the gates 6 at the other side of the crossing, and to this end is formed with an enlargement having a longitudinal slot 77. A bell 105 crank lever 78 is pivotally mounted upon the tie 4, adjacent the link 72 and has a pin 78' engaged through the slot 77, the said lever 78 110 being connected by a link 79 with the inner end of the **T** lever 68. The latter is connected by links 72' and 73' corresponding to the links 72 and 73 with the respective gates 6 in the manner above noted. The link 79 is 115 moved from the right hand side of the track looking at Fig. 1 by the lever 78, but it is moved from the left hand side of the track by virtue of connection with the link 61. To this end the link 61 is formed with a head or 120 lug 80 which engages the angular offset end 81 of a connecting strap 82, the other end of which is similarly offset as at 83, the ends 81 and 83 surrounding the respective links 61 and 79. The link 79 is likewise formed with a bead or lug 84 and an expansive coil spring 85 is interposed between the end 83 and the head 84, the spring 85 serving as a cushioning element to prevent the shocks or vibrations 125 between the links 79 and 61 in the operation 130

of the former from the latter. The various interconnected gate operating elements above described are restored to initial position by a counterbalance weight 86 carried 5 on the elongated projecting end of a bell crank lever 87, pivoted upon one of the ties 3 at the left hand side of the crossing as viewed from Fig. 1 and connected with the adjacent lever 43 by slidably engaged links 88, between which the cushioning spring 89 is interposed, to absorb vibrations incident upon the sudden movement of the lever 87 and weight 86 in their function.

It will be noted that a gap occurs between 15 the operating elements at the crossing 2, and for the purpose of sustaining said elements in the positions to which they have previously been moved upon the approach of the train towards either side of said crossing, operative 20 connections are interposed between one of the members 31 and the adjacent link 61. To this end said link 61 is formed at determinate points with enlargements having longitudinal slots 90, in which are engaged pins 25 91 provided upon the angular arm 92" of a T lever 92, two of such levers being employed and arranged so that their arms 92" point inwardly towards the rails. Links 93 have their ends pivoted at the ends of the aligned 30 arms 92', of the levers 92, and to the ends of two armed levers 94, pivotally mounted upon the other ends of the ties 3 which carry the levers 92. The links 93 are similar in construction to the links 34 and are formed with 35 brackets 95 which contact with the members 31 at each side of the track for limiting the movement of the links 93. For the purpose of holding the members 31 in intimate relation to the adjacent rails 1, springs 96 are 40 employed. As shown, said springs are of the retractile coil type and are engaged with said rails and with the links 93 and with certain ones of the links 34, but it is obvious that other forms of springs may be used and that 45 the arrangement may be correspondingly varied.

It has been previously stated that an alarm is sounded when the gates 6 are initially operated. With this object in view a 50 clock mechanism 97 is mounted on one of the posts 5, and serves to ring a gong 98, by means of a vibrating tapper 99, the mechanism 97 being preferably inclosed in a housing 100 which protects the working parts thereof, from dust and from the influences of the elements. The clock mechanism includes a star ratchet wheel 101 mounted on the prime shaft 102, movement of the ratchet wheel in the direction of the arrow serving to 55 operate the gear train of the clock mechanism and to sound the alarm. For the purpose of rotating the wheel 101 and operating the clock mechanism, a pawl 103 is provided, which is formed to ride loosely over the 60 points of the wheel 101 and which has a

working end 104. The pawl 103 at its rear end is pivoted as at 105 to one arm of a bell crank lever 106 which is pivoted as at 107 upon the post 5 which carries the clock mechanism. The lever 106 is operatively connected with the lever 74 by a link 106' whereby movement of the lever 74 in the performance of its function, will move the pawl 103. It will be apparent that when the gates 6 swing to their open positions, the lever 74 75 will move in a reverse direction and will reset the pawl 103 upon the next tooth of the wheel 101 for a further operation.

It has been previously stated that the crossing gates are started in their movement 80 to close the crossing upon the entrance of the train into the block and that such starting movement is accomplished with a gradual or step-by-step actuation of the parts. The levers 36 and 37 are employed to effect this. 85 The step-by-step action depends upon the novel construction of connecting elements and upon the proportions of the T levers. Accordingly, the following arbitrary proportions have been adopted as an example of the 90 mode of operation, but it is to be understood that such proportions are by no means final and that other proportions which may be found advantageous in use may be employed instead of those herein stated. The extreme 95 T lever 36 has its angular arm 36" working at a distance of one inch from its pivot, and it is assumed that its angular arms 36' work at a distance of two inches from its pivot. The second T lever 36 as well as the third 100 have their angular arms 36" working at a distance of an inch and a half from their pivots, the proportions of the arms 36' being the same as noted in the foregoing instance. The operative connections between the T 105 levers 36 and the prime lever 67 are constituted of links 109 which are counterparts in construction with the exception of the end link, which terminates at its outer extremity in an eye 109' surrounding a pin 110, on the 110 adjacent lever 36. Similar pins are provided on the remaining levers 36, and a pin 110', corresponding in function to the pins 110 is provided on the extreme end of the arm 37".

As shown more particularly in Figs. 2 and 7, each link 109 is formed at its left hand end with an enlargement having a longitudinal slot 111 and at its right hand end with an enlargement having a longitudinal slot 112, 120 the slots 112 being of less length than the slots 111. A pin 113 is provided at the left hand end of each slot 112, and is preferably curved angularly as at 114, to prevent displacement of the parts. The slots 111 and 125 112 at the adjacent ends of the links 109 register and are engaged over the pins 110 and 110'. It will of course be apparent that the eye 109' takes the place of the slot 112 upon the end link 109. The lever 37 is oper- 130

atively connected with the prime lever 67 by a rod or wire 115 which has its outer end flattened and formed with a slot 112' and with a pin 113', similar in construction and arrangement to the slots 112 and pins 113. Considering the links 109 as a series it will be apparent that as a train enters the block and its wheel flanges press the members 31 outwardly, that the links 34 will be successively moved to impart partial rotation to the levers 36 and 37. Movement of the first lever 36, will start the movement of the links 109 as a series and, through the medium of the rod or wire 115 will actuate the lever 67 to operate the gate throwing mechanisms, to be more exact the mechanism for throwing the crossing gate. Movement of the second lever 36 advances the links 109 and rod or wire 115, to further actuate the gate throwing mechanism and movement of the third lever 36 and the lever 37 sustains the links 109, and the rod or wire 115 at the positions to which they have been previously moved, such step-by-step operation being possible by virtue of the novel formation and assemblage of the links and of the proportions of the levers coöperating therewith. As the crossing gates are lowered the alarm above described is sounded. As the train approaches the crossing, the movement of the gates 6 is completed by the operation of the levers 43, 53, and the links 61 and 79 operatively connected by the strap 82 in the manner above detailed.

It will be apparent that the number of links 109 may be increased as desired, and that other levers similar to the lever 37 may be employed for sustaining the crossing gates in their partially lowered positions. The lever 37 is provided at a distance of, for example, one inch from its pivot 35 with a pin 116' over which is engaged the eye 117' of an end link 117, of which a plurality are employed, the links 117 being counterparts in construction and arrangement to the links 109 so that a detailed description thereof is unnecessary. The links 117 are engaged over pins 116 provided upon the levers 38 and the end link 117 is engaged with a pin 118 upon the outer end of the projecting arm 49' of the lever 49. It will thus be seen that the links 117 afford step-by-step connections for operating the gates 12, through the mechanism described successively from the levers 37 and 38. Such operation is started with the lever 37, the pin 116' being disposed as above noted at the distance of an inch from the pivot 35 and is continued by the second and third levers 38, which have their pins 116 disposed respectively at successive distances of an inch and a half and two inches from their pivots 35, so as to multiply the leverage thereof. It would be obviously impracticable to continue the arms 38' of successively increasing length and this method is employed only up to the third lever 38. For the purpose of increasing or multiplying the movement of the levers 38 beyond the third lever, as shown in Fig. 2, the remaining levers have their arms 38' successively shortened, whereby the result outlined above is successfully attained. One of the links 117 at a short distance from the crossing 2 has its pin engaged with a supplemental link 119, the latter being constituted of slidably connected sections, between which a cushioning spring 120 is interposed. The link 119 has its other end engaged with the projecting arm of a bell crank lever 121 mounted on the adjacent tie 3, said lever having its other arm elongated and equipped with a counterbalancing weight 122, the function of which is to restore or reset the links 117 to normal position after the train has passed out of the block, and to prevent the too sudden action of the links when the train is moving at excessively high speed.

In the modified embodiment of the invention illustrated in Figs. 11 and 12, the departure resides in the connection between the links 61 and 79 and more particularly in the construction of the strap and in the employment in connection therewith of novel actuating elements for disengaging the strap from the link 79 to permit of the gates 6 being opened just as soon as a train passes, or while it is passing over the crossing 2. The strap is designated by the numeral 82' and has an offset end 81' which is engaged with the link 61 in the manner previously described. The other end of the strap 82' is formed with a depending yoke 83' which is formed to overlie the link 79 and to engage a lug or stop 83'' and move said link upon movement of the link 61 in the manner previously noted. The strap 82' is formed beyond the yoke 83' with an inclined projection 82'' affording a cam, and which coöperates with a pivoted bell crank lever 123. The lever 123 has one of its ends free for engagement with the projection 82'' and its other end pivotally connected to a link 124 having an angular portion 125 fixed to the adjacent member 31.

In operation, the train enters the block and the flanges of the wheels engage between the rails 1 and the adjacent members 31, forcing the latter outwardly and by virtue of the links 109, lowering the gates 6 to a half closed position. Further movement of the train through the medium of the links 117 and the connections described operates the gates 12 to clear the tracks and close the crossing conjunctively with the gates 6. In the event of the links 117 becoming out of order, the gates 12 will be suddenly operated as the train approaches the crossing through the medium of the links 55 engaged with the levers 43 at each side of the crossing. As the train recedes, the counterbalances 86, 130

122, and the springs 96, restore the parts to normal position. It will be apparent that in the modified embodiment of connection shown in Figs. 11 and 12, when the member 5 31 at one side of the track is moved away from the rail adjacent thereto, the strap 82' will be engaged with the link 79, but when the member 31 moves toward the track under the pressure of the springs 96, the strap 10 82' will be disengaged from the link 79 and the counterbalances 7 will open the gates 6, at which time the system as an entirety will be restored to normal position whereby the 15 yoke 83' will overhang the rear end of the stop 83''. The cushioning spring designated 85' surrounds the link 61 and bears against a stop collar 85'' and against the end 81' which is loosely slidably on said link. The position 20 of the lever 123 is such that in the normal position of parts it will be engaged with the projection 82'' to hold the strap 82' out of engagement with the link 79, but such engagement is effected as soon as the link 61 commences its operative movement, the projection 25 82'' moving with relation to the lever 123 until the yoke 83' is engaged with the link 79, in the manner described.

The invention is susceptible of manifold variations and modifications, and accordingly 30 it will be understood that the disclosure herein contained is to be regarded in the light of example. The parts may be materially varied from the arrangement shown in accordance with the conditions of use, an 35 example being as when mounting the associated parts with relation to curved tracks.

The system as a whole is comparatively inexpensive to manufacture, simple in construction, and highly practical and efficient 40 in use.

What is claimed is:

1. In an apparatus of the type set forth, 45 the combination with train operated gate actuating means of a vertical rock shaft, operatively connected with said means, a gate having portions of its frame loosely surrounding said rock shaft, and projecting on each side thereof, and resilient connections between said shaft, and the projecting portions of said gate on each side thereof.

2. In an apparatus of the type set forth, 55 the combination with train operated gate actuating means of a vertical rock shaft, operatively connected with said means, a gate having portions of its frame loosely surrounding said rock shaft, and projecting on each side thereof, and retractile coil springs secured in oppositely disposed pairs to said shaft and to said projecting portions of said frame on each side thereof.

3. In an apparatus of the type set forth, 60 the combination with a vertical gate shaft and its operating means, of a frame carried upon said shaft, and including a horizontally 65 projecting pintle, and a gate including a

frame having portions thereof loosely surrounding said pintle as a pivot.

4. In an apparatus of the type set forth, 70 the combination with a vertical gate shaft and its operating means, of a frame carried upon said shaft, and including a horizontally projecting pintle, a gate including a frame having portions thereof surrounding said pintle as a pivot and resilient connections between said first and second named frames. 75

5. In an apparatus of the type set forth, 80 the combination with a vertical gate shaft and its operating means, of a frame carried upon said shaft and including a horizontally projecting pintle, a gate including a frame having portions thereof surrounding said pintle as a pivot, and a retractile coil spring having its ends engaged with said respective frames. 85

6. In an apparatus of the type set forth, 90 the combination with track rails, a crossing, crossing gates, track gates, means for normally holding said crossing and track gates in respectively open and closed positions, and train actuated members, of gate operating mechanisms arranged at each side of said crossing, and comprising prime levers, operative connections between said prime levers and said train actuated members, said connections including a slidable link, operative connections between said prime levers and said track rail gates, mechanism for operating said crossing gates, and operative connection between said slidable links and said last named mechanism. 95

7. In an apparatus of the type set forth, 100 the combination with track rails and a crossing, of track gates including projecting arms, arranged on each side of said crossing and mounted for horizontal swinging movement, train actuated members, prime levers arranged on each side of said crossing, operative connections between said members and said prime levers, links directly connecting each of said prime levers, with one of said 105 gates on the side of the crossing adjacent thereto, a two armed lever pivoted between its ends, a link connecting said prime lever with one end of said two-armed lever, and a link connecting the other end of said two-armed lever with the other of said gates on the side of the crossing adjacent thereto. 110

8. In an apparatus of the type set forth, 115 the combination with track rails and a crossing, of track rail gates, operating mechanism therefor, train actuated members mounted adjacent to said track rails, a plurality of slidably connected elements interposed between said train actuated members and said operating mechanism and means for successively moving each of said members to impart a successive step-by-step operation to said operating mechanism. 120

9. In an apparatus of the type set forth, 125 the combination with track rails and a cross-

ing, of track rail gates, crossing gates, means for operating said track rail gates to clear said track rails, means for operating said crossing gates to close said crossing, train actuated members mounted adjacent to said track rails, a plurality of slidably connected elements engaged with said track rail gate operating means, a plurality of slidably connected elements engaged with said crossing 5 gate operating means and connections between said train actuated members and both series of said slidably connected elements for successively moving each of said members in its respective series to impart a successive 10 step-by-step operation to said respective operating means.

10. In an apparatus of the type set forth, the combination with a crossing and crossing gates, of operating mechanism for said gates 15 including a slidable element, a second slid-

able element coöperating with said first slidable element to actuate said operating mechanism, a connection carried by said second slidable element and formed to engage said first slidable element, said connection being 25 slidable with the element by which it is carried, and train operated means formed to engage said connection and in such engagement to disengage the same from said first slidable element and to permit of movement thereof 30 upon the restoration of the gates to normal position, independently of said second slidable element.

In testimony whereof, I affix my signature, in presence of two witnesses.

ELMER E. SAMPSON.
